ATTORNEY

UNITED STATES PATENT OFFICE.

CHARLES P. CATLIN, OF JERSEY CITY, NEW JERSEY.

DESIGN FOR AN OIL CAN.

Application filed June 24, 1926. Serial No. 18,161. Term of patent 14 years.

To all whom it may concern:

Be it known that I, CHARLES P. CATLIN, a citizen of the United States, residing at Jersey City, county of Hudson, and State of New Jersey, have invented a new, original, and ornamental Design for an Oil Can, of which the following is a specification, reference being had to the accompanying drawings, forming a part thereof.

In the drawings:

Fig. 1 is a front elevation and Fig. 2 is a side elevation of an oil can embodying the design of the present invention.

What is claimed is:

The ornamental design for an oil can, substantially as shown.

CHARLES P. CATLIN.
